UNITED STATES PATENT OFFICE

2,665,437

MACHINE FOR FORMING SHOE QUARTERS

Anton E. Diessel, Fenton, Mo., assignor to International Shoe Company, St. Louis, Mo., a corporation of Missouri

Application December 4, 1950, Serial No. 198,961

5 Claims. (Cl. 12—51)

1

The present invention relates generally to shoe forming machines, and more particularly to a novel machine adapted to shape one-piece rear shoe quarters.

Briefly, the present invention comprises a stationary electrically heated supporting form of appropriate shape and a movable, molded, flexible saddle adapted to embrace the form in a combined wrapping and clamping action, an appropriate linkage arrangement being provided to impart the desired motion to the saddle. The movement of the saddle is manually effected through adjustable spring tension to provide a desired clamping force and a releasable latching arrangement is provided to maintain the saddle in clamping position.

The rear quarter of a shoe is that part in the back of the shoe that passes around the heel, and, in the case of high shoes, around the ankle. Shoes generally are made with the rear quarter in two parts, the parts being cut in such a way as to form an appropriate shape around the heel and ankle and then stitched together at the back. The seam thus formed is covered by a stay attached thereto, the stay serving both to reinforce the joint and to improve the appearance.

A less common type of shoe is known as the one-piece or whole quarter shoe, which, as the name implies, has the rear quarter made from a single piece of leather. One method of constructing such a quarter has been to form the part by crimping in a machine with special jaws and blade, after which the parts are trimmed or cut over and finally assembled with the rest of the shoe.

It is an object of the present invention to provide a novel one-piece quarter forming machine which eliminates the necessity for crimping and cutting over.

It is another object of the present invention to provide a novel one-piece quarter forming machine which does not make deleterious rubbing or frictional contact with the leather.

It is another object of the invention to provide a novel machine for shaping one-piece rear shoe quarters, either before or after being attached to other parts of the shoe.

It is another object of the invention to provide a novel machine for shaping one-piece rear shoe quarters without wrinkling, bunching or creasing the leather.

It is another object of the invention to provide a manually operable mechanism for effecting a

desired action in a one-piece quarter forming machine.

Other objects and advantages will be obvious from the following description taken with the accompanying drawings, in which:

Fig. 1 is a fragmentary front elevational view of a plurality of one-piece quarter forming machines mounted on a single frame, each machine embodying the teachings of the present invention;

Fig. 2 is a side elevational view of the setup of Fig. 1 with the mounting frame shown in section;

Fig. 3 is an enlarged, fragmentary, front elevational view showing the principal forming elements of the machine;

Fig. 4 is an enlarged, fragmentary, side elevational view showing the principal forming elements of the machine;

Fig. 5 is a further enlarged, side elevational view of a shoe supporting form;

Fig. 6 is a vertical, sectional, elevational view taken generally along the line 6—6 of Fig. 5;

Fig. 7 is a side view of an assembled shoe having a one-piece rear quarter prior to the quarter being formed;

Fig. 8 is a fragmentary view showing the shoe of Fig. 7 mounted for forming of the one-piece quarter in accordance with the teachings of the present invention;

Fig. 9 is a side view of the shoe of Fig. 7 after the forming operation;

Fig. 10 is a further enlarged front elevational view similar to Fig. 3;

Fig. 11 is a further enlarged side elevational view similar to Fig. 4; and

Fig. 12 is a horizontal sectional view taken generally along the line 12—12 of Fig. 11.

Referring to the drawings more particularly by reference numerals, 15 indicates generally a quarter forming machine constructed in accordance with the teachings of the present invention. The quarter forming machine 15 includes a quarter forming device 16 and an operating mechanism 17. A plurality of machines 15 are illustrated mounted on a single angle iron supporting frame 18.

The forming device 16 includes a shoe supporting form 20 of appropriate shape as indicated in Figs. 5 and 6. This form 20 is preferably of cast iron with a nickel plated exterior finish and is adapted to be heated by an electrical resistance element 21 (Figs. 4 and 8) inserted into a longitudinal bore 22. A thermostatic bulb element 23 is similarly received in a second longi-

tudinal bore 24 in the form 20 for maintaining the temperature thereof at a predetermined degree. The form 20 includes a mounting sleeve 25 which is received in a mounting base 26, being rigidly secured in the latter by means of a set screw 27 engaging a flat horizontal surface 28 formed on the sleeve 25. The mounting base 26 is, in turn, secured to a base plate 29 by means of cap screws 30.

A standard 35 also secured to the base plate 29 as by cap screws 36 comprises a vertical channel portion 38 which is backed up by an integral brace 37 to impart added rigidity. Vertical retaining strips 39 secured by cap screws 40 on each side of the channel portion 38 cooperate therewith in forming a vertical T-slot 41. A crosshead 45 having a T-shaped horizontal section is slidably disposed in the T-slot 41 and has a face 46 disposed substantially forwardly of the strips 39 and the cap screws 40 thus enabling an extension arm 47 rigidly secured in a horizontal channel 48 in the face 46 of the crosshead 45 to move freely with the crosshead 45. A cap screw 49 secures the arm 47 to the crosshead 45.

The arm 47 extends forwardly from the crosshead 45 and carries at its unsupported end a yoke 50 having oppositely extended horizontal clevis arms 51 and twin parallel vertical elements 52 by means of which it is pivotably secured to the arm 47 by a bolt 53 as best shown in Figs. 3 and 4. A saddle link 54 is carried at the outer extremity of each clevis arm 51, being pivoted thereto at points intermediate the respective ends of the links 54 by means of rivet pins 55. A molded flexible saddle 56 which may be formed from canvas and felt, or similar material, is disposed between the two saddle links 54 and is secured at its side ends by means of bolts 57 to angle brackets 58 pivotally attached to respective lower ends of the links 54 by means of rivet pins 59. A tension spring 60 hooked between respective upper ends of the links 54 biases the links 54 and consequently the saddle 56 to positions adjustably predetermined by cap screws 61 threadedly engaging the vertical elements 52 and secured in adjusted position by jamb nuts 62.

The angle iron frame 18 is fabricated as clearly shown in Figs. 1 and 2 of the drawings, and carries the base plate 29 at a top level thereof, the plate 29 being secured by bolts 66. The frame 18 also carries the mechanism 17 through which the forming device 15 is operated.

The mechanism 17, as best shown in Figs. 1 and 2, comprises an eye bolt 70 pivotally attached by a cap screw 71 to the crosshead 45. The threaded end of the eye bolt 70 is connected to a clevis bolt 72 through an adjustable shackle 73 secured by jamb nuts 74 and 75. A clevis end 76 of the bolt 72 is pivotally attached by means of a pin 77 to one end 78 of a lever 79 pivotally mounted to a bracket 80 bolted to an intermediate horizontal member 81 of the frame 18. A weight 82 is adjustably disposed on a free end 83 of the lever 79, being secured in adjusted position thereon by a screw 84. It is obvious that the weight 82 biases the crosshead 45 and parts connected thereto toward their most upward position as determined by abutment of the lever 79 with the intermediate member 81 of the frame 18.

A compression spring 85 is connected also to the clevis end 76 of the bolt 72 and to a hook bolt 86 by means of wire stirrups 87 inserted there-

through. The threaded end of the hook bolt 86 is connected to a clevis bolt 88 through an adjustable shackle 89 secured by jamb nuts 90 and 91. The clevis end of the bolt 88 is pivotally connected intermediate the ends of a treadle bar 92 pivotally mounted at one end to a bracket 93 bolted to a lower horizontal member 94 of the frame 18. A foot pad 95 is welded to the free end of the treadle bar 92 and it is obvious that a downward push on the pad 95 will act through the spring 85 to cause the crosshead 45 and parts connected thereto to move toward their most downward position as determined by a tight clamping engagement of the flexible saddle 56 with the form 20 or with a shoe quarter disposed thereon. A bracket plate 96 bolted to a vertical member 97 of the frame 18 is adapted to maintain the treadle bar 92 in a depressed position when the later is moved by the operator so as to abut a lower edge 97 of the bracket plate 96.

The frame 18 also supports the electrical control equipment required for the several machines 15. This equipment is conventionally arranged and comprises a switch box 100, thermostats 101, conduits 102, and outlet boxes 103.

Operation

In operating the quarter forming machine 15, an assembled shoe 105 is placed over the thermostatically controlled, electrically heated supporting form 20 as best shown in Fig. 3, so that the inside of the heel of the shoe abuts and adjustable gauge knob 106 threadedly received in the forward end of the form 20 as best shown in Fig. 4. The treadle bar 92 is then pushed downwardly by foot pressure and shifted slightly sidewardly so as to hook under the bracket 96.

As the treadle bar 92 is moved downwardly, the crosshead 45 and all parts supported thereby also descend, the initial descent being without relative movement between any of said parts. When the center of the descending saddle 56 makes contact with the back of the shoe 105, however, it is obvious that the lower ends of the saddle links 54 will be drawn towards each other, so as, in effect, to wrap the sides of the saddle around the rear quarter of the shoe 105. This wrapping action is accomplished substantially without rubbing contact upon the shoe quarter and the latter pressed against the heated form 20 is quickly and permanently shaped to a desired conformation, whereupon the treadle bar 92 is released so as to allow the weight 82 to lift the saddle 56 and thus permit the shoe 105 to be removed in the form of the shoe 109 of Fig. 9. Obviously, the tension spring 60 causes the movement of the saddle links 54 to be reversed during the retraction of the saddle so as to unwrap the shoe quarter again without rubbing. With a plurality of machines 15 mounted on a frame 18 as depicted in Figs. 1 and 2, an operator may load each in turn, and then return immediately to unload and reload in rotation. The time interval during which each shoe quarter is desired to be wrapped against a form 20 will, of course, dictate a suitable number of machines 15 to be thus assembled.

The shaping of a one-piece rear shoe quarter, of course, need not be deferred until the shoe is completely assembled. The machine 15 may, therefore, also be used to shape a one-piece quarter before the upper parts of the shoe are stitched together. When thus employed, it is preferable to use a gauge angle 107 attached to

the form 20 by a screw 108 as best shown in Fig. 6. The angle 107 constitutes an abutment against which the edge of the quarter may be placed to insure correct positioning on the form 20.

It has been found particularly efficient to form one-piece shoe quarters in two operations, the first being performed on the quarter alone and the second being performed just prior to final finishing after the shoe is completely assembled. Obviously, the machine 15 is adapted to perform both operations, the forms 20, including the proper knob 106 or angle 107 and the saddles 56, however, being different for the two operations.

It is obvious that there has been described a machine and method for forming one-piece rear quarters for shoes which attains the objects and advantages sought therefor.

It is to be understood that the foregoing description and the accompanying drawings have been given by way of illustration and example. It is also to be understood that changes in form of the several parts, substitution of equivalent elements or steps, and rearrangement of parts or steps which will be readily apparent to one skilled in the art are contemplated as within the scope of the present invention which is limited only by the claims which follow.

What is claimed is:

1. In a machine for shaping one-piece rear shoe quarters, a forming device comprising, in combination, a heated stationary form to receive a rear shoe quarter, a flexible form to cooperate with said stationary form to effect a permanent change in the shape of a rear shoe quarter mounted therebetween, said flexible form being of non-metallic construction, and manually operable reciprocable means connected to opposite ends of said flexible form for imparting a wrapping motion thereto only when a central portion thereof is restrained from translatory movement.

2. In a machine for shaping one-piece rear shoe quarters, a forming device comprising, in combination, a heated stationary form to receive a rear shoe quarter, a flexible form to cooperate with said stationary form to effect a permanent change in the shape of a rear shoe quarter mounted therebetween, said flexible form being of non-metallic construction, and a manually operable reciprocable spring-biased system of links connected to opposite ends of said flexible form for imparting a wrapping motion thereto only when a central portion thereof is restrained from translatory movement.

3. In a machine for shaping one-piece rear shoe quarters, a forming device comprising, in combination, a heated stationary form to receive a rear shoe quarter, a yoke disposed above said stationary form and mounted for vertical reciprocation, a pair of links pivotally mounted to said yoke for oscillatory movement, a spring connected between said links for biasing the oscillatory movement thereof, means to adjust the extent of said oscillatory movement, and a flexible form of non-metallic construction connected between said links so as to straddle said stationary form, said links and said flexible form being adapted to

move downwardly during an initial downward movement of said yoke without relative movement therebetween until a portion of said flexible form is restrained by engagement with a rear shoe quarter disposed on said stationary form, said links and said flexible form being adapted to move relative to one another during a subsequent downward movement of said yoke, said relative movement being against the biasing action of said spring, and comprising a wrapping motion of said flexible form, whereby said flexible form may cooperate with said stationary form to effect a permanent change in the shape of a rear shoe quarter mounted therebetween.

15 4. In a machine for shaping one-piece rear shoe quarters, in combination, a forming device including a reciprocable member, and a manually operable mechanism to impart a reciprocating motion to said reciprocable member comprising a foot treadle, a resilient connection between said treadle and said reciprocable member whereby a downward movement of said treadle may exert a downward pull of limited force on said reciprocable member, means to latch said treadle in a downward position and a counterweight connected to said connection between said treadle and said reciprocable member adapted to exert an upward push on said reciprocable member upon release of said treadle.

20 5. In a machine for shaping one-piece rear shoe quarters, in combination, a supporting frame, a forming device including a reciprocable member mounted at a top level of said frame, and a manually operable mechanism for reciprocating said reciprocable member comprising an adjustable link pivotally connected to said reciprocable member, a lever mounted at an intermediate level of said frame and pivotally connected to said adjustable link, a counterweight adjustably mounted on said lever so as to bias said adjustable link upwardly, a foot treadle mounted at a lower level of said frame, a link assembly connected between said adjustable link and said treadle, said link assembly including a compression spring and opposed stirrups extending therethrough, said treadle being adapted to act through said link assembly so as to exert a downward pull on said adjustable link against the biasing action of said counterweight, and means for latching said treadle in a downward position so as to maintain said downward pull without attention from an operator.

ANTON E. DIESSEL.
